UNITED STATES PATENT OFFICE

148,063

DESIGN FOR A HANDBAG LOCK CLOSURE

Zoltan Grosz, New York, N. Y.

Application February 20, 1947, Serial No. 137,040

Term of patent 3½ years

(Cl. D87—2)

To all whom it may concern:

Be it known that I, Zoltan Grosz, a citizen of no country, residing in New York city, county of New York, and State of New York, have invented a new, original, and ornamental Design for a Handbag Lock Closure, of which the following is a specification, reference being had to the accompanying drawing, forming part thereof, wherein,

Figure 1 is a top plan view of a handbag lock closure showing my new design in closed position.

Figure 2 an elevational view thereof taken along line 2—2 of Figure 1.

Fig. 3 is a view of the handbag lock closure showing its parts in separated position. The turn lock member in side elevation, is shown in open position, while the plate member is shown as a top plan view.

Figure 4 is a bottom plan view of the handbag lock closure in closed position, as shown in Figure 2.

I claim:

The ornamental design for a handbag lock closure, substantially as shown and described.

ZOLTAN GROSZ.
